UNITED STATES PATENT OFFICE

158,799

DOOR FOR A REFRIGERATOR EVAPORATOR

Carl Reynolds, Jr., Birmingham, Mich., assignor
to Avco Manufacturing Corporation, Cincinnati,
Ohio, a corporation of Delaware

Application April 1, 1949, Serial No. 1,746

Term of patent 3½ years

(Cl. D67—3)

To all whom it may concern:

Be it known that I, Carl Reynolds, Jr., a citizen of the United States, residing at Birmingham, Michigan, in the county of Oakland, have invented a new, original, and ornamental Design for a Door for a Refrigerator Evaporator, of which the following is a specification, reference being had to the accompanying drawing, forming a part thereof.

In the drawing:

Fig. 1 is a front elevational view of a door for a refrigerator evaporator embodying my new design;

Fig. 2 is a top plan view thereof;

Fig. 3 is a bottom plan view thereof;

Fig. 4 is a right hand elevation thereof;

Fig. 5 is a left hand elevation thereof;
Fig. 6 is a sectional view taken along the line 6—6 of Fig. 1.

Fig. 7 is a rear elevation thereof.

I claim:

The ornamental design for a door for a refrigerator evaporator, as shown.
